UNITED STATES PATENT OFFICE.

JOHN H. DERBY AND EDWARD E. DERBY, OF GREENSBURG, PENNSYLVANIA.

FOLDING BOX OR CRATE.

No. 900,492.

Specification of Letters Patent.

Patented Oct. 6, 1908.

Application filed March 6, 1908. Serial No. 419,494.

To all whom it may concern:

Be it known that we, JOHN H. DERBY and EDWARD E. DERBY, citizens of the United States of America, residing at Greensburg, in the county of Westmoreland and State of Pennsylvania, have invented certain new and useful Improvements in Folding Boxes or Crates, of which the following is a specification, reference being had therein to the accompanying drawing.

This invention relates to folding boxes and crates, and the objects of our invention are, first, to provide a novel box or crate that can be folded to occupy a comparatively small space when not containing merchandise; second, to reduce the bulk of boxes or crates during return shipment; third, to obviate the necessity of nailing or otherwise securing the lid or cover upon a box or crate; and fourth, to provide a simple, inexpensive and durable folding box or crate that can be easily and quickly collapsed.

We obtain the above objects by a structure that will be presently described and then specifically pointed out in the appended claims.

Referring to the drawing forming part of this specification, Figure 1 is a front elevation of our box or crate as set up for actual use. Fig. 2 is a plan of the same with the lid or cover detached. Fig. 3 is an end view of a box or crate in a set up position. Fig. 4 is a cross sectional view of the same. Fig. 5 is a longitudinal sectional view of the box or crate as knocked down or in a folded position, and Fig. 6 is an end view of the same.

In the accompanying drawings, 1 designates the bottom of the box or crate, which is supported by transverse cleats 2 arranged at the end of said box or crate. The longitudinal edges of the bottom 1 are provided with a front board 3 and a rear board 4, the latter being of greater height than the former.

Hinged to the front board 3 is a front wall 5 having its ends constructed to provide vertical grooves 6. Hinged to the rear board 4 is a rear wall 7 having its ends constructed to provide vertical grooves 8. Adapted to engage in the grooves 6 and 8 are the edges of end walls 9, said end walls being pivotally connected to the bottom 1 as at 10, whereby the end walls can be folded inwardly upon the bottom 1, as illustrated in Fig. 5 of the drawings.

To temporarily hold the walls of the box or crate, while the lid or cover is being placed thereon, we provide the ends of the front and rear walls 5 and 7 respectively with eyelets 11, to receive double hooks 12 pivotally connected to the inner sides of the end walls 9.

The upper edge of the rear wall 7 is slotted, as at 13 and provided with eyelets 14. Connected to said eyelets by transverse rods 15 is a lid or cover 16, said lid or cover having a front flanged edge 17 provided with a hook 18 adapted to engage in an eyelet 19, carried by the front wall 5 of a box or crate. The hook 18 is employed for maintaining the lid or cover 16 in a closed position and to maintain said lid or cover in a folded position, we provide the rear board 4 with hooks 20, for engaging in the looped shaped ends 21, of the rods 15.

The front edge of the lid or cover is provided with an eyelet 22 adapted to receive the hook 18 of the lid or cover and maintain the same in a folded or collapsed position.

After the end walls 9 have been folded inwardly upon the bottom 1, the front wall 5 is folded inwardly, and then the rear wall 7, but prior to folding the rear wall 7, the lid or cover is moved to lie parallel therewith. This is accomplished by the rods 15 sliding in the eyelets 14. After the rear wall 7 and the lid or cover 16 has been folded, the hooks 20 and 18 are placed in engagement with the looped shaped ends 21 of the rods 15 and the eyelet 22. These hooks are adapted to firmly hold the collapsible parts of the box or crate in a folded position, while the same is being handled.

A novel characteristic of our invention resides in the manner in which the lid or cover is connected to the rear wall 7. The rods 15 and the eyelets 14 constitute a sliding hinge, while the ends of said rods constitute means for locking the lid or cover to the rear board 20.

We reserve the right to make such structural changes in our invention as are permissible by the appended claim.

Having now described our invention what we claim as new, is:—

A folding crate comprising a bottom, a front board carried by said bottom, a rear board carried by said bottom, a front wall hinged to said front board and provided with slots, a rear wall hinged to said rear board, end walls pivotally connected to said bottom, said front and rear wall having grooves

to receive the vertical edges of said end walls, eyelets carried by said rear wall, a lid or cover, rods connected at one end to said lid or cover and extending through said slots and 5 engaging in said eyelets, said rods having the other end thereof looped and connected to said cover, hooks carried by said rear board, adapted to engage in the loop shaped ends of said rods for maintaining said crate in a col- 10 lapsed form, and means carried by the front

edge of said lid or cover for maintaining said lid or cover in a closed position.

In testimony whereof we affix our signatures in the presence of two witnesses.

JOHN H. DERBY.
EDWARD E. DERBY.
